CLAIM

USPC ... D26/37-39, 40-41, 51-52, 54, 93-94, 98,

The ornamental design for a baby night light, as shown and described.

DESCRIPTION

FIG. 1 is a front elevational view of a baby night light showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof;

FIG. 8 is a second perspective view thereof; and,

(Continued)

FIG. 9 is a perspective view of the article in an alternative state.

The broken lines shown in the drawings depict portions of the article that form no part of the claimed design.
